UNITED STATES PATENT OFFICE.

ALBERT L. SESSIONS, OF BRISTOL, CONNECTICUT.

CEILING-PLATE.

1,216,737.

Specification of Letters Patent.

Patented Feb. 20, 1917.

Application filed April 26, 1912. Serial No. 693,500.

To all whom it may concern:

Be it known that I, ALBERT L. SESSIONS, a citizen of the United States, and a resident of Bristol, in the county of Hartford and State of Connecticut, have invented a new and Improved Ceiling-Plate, of which the following is a specification.

My invention relates to the class of devices employed for covering an opening between a pipe and wall or ceiling through which opening the pipe passes to provide a finish, and an object of my invention, among others, is to provide a device of this class in which the sections have improved fastening means for securing them in place.

One form of device embodying my invention and in the construction and use of which the object herein set out, as well as others, may be attained is illustrated in the accompanying drawings in which—

Figure 1 is a plan view of a sectional ceiling plate embodying my invention, the sections being shown separated.

Fig. 2 is a view in section through a wall or ceiling and in elevation of a broken section of pipe showing my improved ceiling plate in place, parts of the plate being broken away to show construction.

Fig. 3 is a detail view showing the sections of the plate in unlocked engagement, the position of the outer surface of the pipe being denoted by dotted lines.

Fig. 4 is a view showing a modified form of the invention.

In the accompanying drawings the numeral 6 denotes, in general, a wall or ceiling having an opening 7 for a pipe 8. My improved ceiling plate consists of two sections 9 preferably formed of sheet metal struck to shape, and having spring fingers, to be hereinafter described, projecting from what I term the under surface of the plate, this under surface being that surface located against the wall or ceiling when the plate is in position.

The sections of the plate are duplicates each of the other, each having an overturned flap 10 located within a flange 11, each section being semicircular in form and the flaps being supplied from metal taken from within the semicircle. Each flap is located at such distance from the base of the plate as to provide a socket 12 into which a tongue 13 from the opposite plate projects. A rib 14 may be formed at the base of each flap.

A locking slot 15 is formed in the side of

each tongue to receive a locking stud 16 upturned from the edge of the opposite section of the plate, this locking stud being located at one side of the socket that receives the 60 tongue.

In assembling the device the tongues are inserted in their respective sockets and the two sections of the plate forced together until their edges meet, and then by a radial 65 movement of the sections one upon the other the locking studs are caused to engage the locking slots and thus prevent separation of the plate.

In order to retain the sections in the locked engagement just described the locking fingers 17 are so located that their pressure upon the pipe will be in a direction to cause the locking studs to be retained within the locking slots, in the construction here- 70 shown the locking slots being located on the outer edge of the tongue. The fingers 17 are each located on that edge of its section abutting against the edge of the opposite section having the overturned flap. It will 75 be understood that the fingers are sufficiently resilient to enable the sections to be moved radially under proper force to disengage the locking stud from the locking slot. Another set 18 of spring fingers are located prefer- 80 ably midway between the fingers 17 to assist in positioning the plate.

In the form of the device shown in Fig. 4 a rib 20 is formed on one or both of the tongues, this rib engaging a recess 21 in the 90 under surface of the overturned flap. The rib and recess are so inclined that as the two sections of the plate are forced together they will also be forced in a radial direction to cause the locking stud to engage the 95 locking slot.

I do not deem it absolutely essential to the invention that a positive lock for preventing separation of the sections shall exist, and in fact the construction herein shown may be 100 changed to a greater or lesser extent and yet embody the invention.

While there has been shown and described herein fingers which resiliently grasp the pipe it will be understood that any means 105 for obtaining this pressure against the pipe may be employed, and I do not therefore limit the structure to this resilient feature as contained in the spring fingers alone.

I claim—

1. A ceiling plate including two sections arranged to encircle a pipe, each of the sec-

tions having a flap overturned from its inner edge near its end, a stud projecting from the end of each section at a point opposite the bend of said flap, and a projecting tongue from the end of each section near its inner edge positioned to pass between the curved overturned edge of the flap and said stud.

2. A ceiling plate including two sections 10 of semicircular form arranged to encircle a pipe, said sections having flaps bent in opposite directions from opposite inner edges near the ends thereof, said flaps extending toward the outer edge of each section, and a 15 tongue projecting from the end of each section near the inner edge thereof in position to pass underneath said overturned flaps and limit relative lateral movement of said sections by engagement with the bent edges of 20 said flaps.

3. A ceiling plate including two sections arranged to encircle a pipe, one of the sections having an overturned flap forming a recess, a tongue on the opposite section arranged to pass into said recess and having a 25 locking notch, and a stud upon the opposite section arranged to engage said notch to hold the sections in locked engagement.

4. A ceiling plate including two sections 30 arranged to encircle a pipe, one of the sections having an overturned resilient flap forming a recess, a tongue on the opposite section arranged to pass into said recess, said tongue having a locking notch, a locking stud arranged to engage said notch, and means upon the sections to resiliently hold 35 the parts in locked engagement.

5. A ceiling plate including two sections arranged to encircle a pipe, one of the sections 40 having an overturned flap forming a recess, a tongue upon the other section located to pass into said recess, said tongue having a locking slot, a locking stud upon the opposite section arranged to engage the 45 locking slot, and a spring finger positioned upon the sections to oppose movement of the sections to disengage said stud from said slot.

6. A ceiling plate including two sections 50 arranged to encircle a pipe, each of the sections having on one end an overturned flap

forming a recess and a tongue projecting from the opposite end to engage a recess formed by a flap, each tongue having a locking slot, a stud to engage said locking slot, 55 and spring fingers projecting from each of the sections and located to yieldingly resist movement of the sections to disengage the studs from the slots.

7. A ceiling plate including two sections 60 arranged to encircle a pipe, each of the sections having on one end a loop open on one side, a tongue projecting from the opposite end of each section to engage a loop on the opposite section and spring fingers projecting from each of the sections and located to yieldingly resist movement of the sections in a direction to move a tongue out of the open side of its engaging loop.

8. A ceiling plate including two sections 70 arranged to encircle a pipe, one of the sections having a flap overturned from the metal originally composing the center of the plate and forming a recess and the other a tongue arranged to pass into said recess and 75 limit relative lateral movement of said sections by engagement with the bent edges of said flaps, means upon the sections for holding them in locked engagement, and means for resiliently resisting movement of the 80 sections to unlock them.

9. A ceiling plate including two sections duplicates each of the other and each having a socket at one end and a tongue at the other end arranged to pass into said socket and 85 thereby limit the lateral movement of the sections one with respect to the other, and means for holding the sections in locked engagement.

10. A ceiling plate including two sections 90 duplicates each of the other and each having at one end a socket formed by a flap overturned from the metal originally composing the center of the plate and the opposite end of each section having a tongue adapted to 95 enter the socket formed by said overturned flap and thereby limit the lateral movement of the sections one with respect to the other.

ALBERT L. SESSIONS.
